US00D900241S

(12) **United States Design Patent** (10) **Patent No.:** **US D900,241 S**
(45) **Date of Patent:** **** Oct. 27, 2020**

(54) **SCOOTER**

(71) Applicant: **RAZOR USA LLC**, Cerritos, CA (US)

1,391,312 A 9/1921 Gebhardt
1,534,601 A 4/1925 Matveyeff
1,570,189 A 1/1926 Sturm
(Continued)

(72) Inventor: **Ian Desberg**, Cerritos, CA (US)

FOREIGN PATENT DOCUMENTS

(73) Assignee: **RAZOR USA LLC**, Cerritos, CA (US)

CN 2 457 013 Y 10/2001
CN 201538397 U 8/2010
(Continued)

(**) Term: **15 Years**

(21) Appl. No.: **29/711,903**

(22) Filed: **Nov. 4, 2019**

Related U.S. Application Data

(63) Continuation of application No. 29/674,371, filed on Dec. 20, 2018, now Pat. No. Des. 866,675, which is a continuation of application No. 29/643,133, filed on Apr. 4, 2018, now Pat. No. Des. 837,303, which is a continuation of application No. 29/577,036, filed on Sep. 8, 2016, now Pat. No. Des. 815,215.

U.S. PATENT DOCUMENTS

606,525 A 6/1898 Dunning
628,433 A 7/1899 Finch
730,622 A 6/1903 Milton
1,297,282 A 3/1919 White
1,345,038 A 6/1920 Uppling

FIG. 1 is a top, rear, left-side perspective view showing a scooter of my design;

FIG. 2 is a close-up view of a portion thereof;

FIG. 3 is a bottom, front, left-side view thereof;

FIG. 4 is a left-side view thereof;

FIG. 5 is a right-side view thereof;

FIG. 6 is a front view thereof;

FIG. 7 is a rear view thereof;

FIG. 8 is a top view thereof; and,

FIG. 9 is a bottom view thereof.

The dot-dash line in FIG. 2 represents the boundary of the enlarged partial view. All other broken lines illustrate portions of the scooter that form no part of the claim. None of the broken lines form a part of the claimed design.

1 Claim, 8 Drawing Sheets

US D900,241 S
